UNITED STATES PATENT OFFICE.

ARTHUR L. COCHRANE, OF TORONTO, ONTARIO, CANADA.

CLAMP.

Application filed April 8, 1922. Serial No. 550,903.

To all whom it may concern:

Be it known that I, ARTHUR L. COCHRANE, of the city of Toronto, in the county of York, Province of Ontario, Canada, a subject of the King of Great Britain, have invented certain new and useful Improvements in Clamps, of which the following is a specification.

This invention relates to devices for fastening ropes, ties, straps, webbing and the like and my object is to devise a clamp particularly adapted for use with boots and shoes to secure the ends of the laces used therewith which is simple and neat and which may, to a considerable extent, be concealed between the shoe upper and its lining.

I attain my object by means of the construction hereinafter described and illustrated in the accompanying drawings in which

Fig. 1 is a perspective view of part of a boot provided with my improved clamp;

Fig. 2 a longitudinal section of the clamp as applied to a boot and on a larger scale;

Fig. 3 a plan view of the same; and

Fig. 4 a longitudinal section of the clamp with the clamping member in the open position.

In the drawings like numerals of reference indicate corresponding parts in the different figures.

1 is a body member, preferably formed of sheet metal, stamped to shape and adapted for connection to the boot in the manner hereinafter described. To this body member is hinged a clamp member 2, which is formed as an open frame. In the preferred construction, one side 3 of the clamp member is offset to lie below the body member and to form at each end a journal 4, each engaging one of the notches 5 formed at opposite sides of the body member.

Formed on or connected with the body member is a knob 6, preferably of hemispherical form as shown but which may be of any convex shape substantially without a neck adjacent the body member. The side 7 of the clamp member opposite the side 3 is shaped to co-operate with the knob at the side thereof remote from the hinge to clamp a lace passed between them as indicated in Fig. 1. The knob being circular in plan, the side 7 is preferably made approximately semi-circular in plan as indicated particularly in Fig. 3. One side of the clamp

member is preferably omitted as shown to facilitate the engagement of a lace between the clamp member and knob.

To further facilitate the introduction of the lace, it is preferable that the free end 8 of the side 7 be slightly knobbed and turned upwardly as shown particularly in Fig. 4. This end, through its shape, is also readily engageable by the user's finger when it is desired to raise the clamp member from the clamping position. A lip 9 is also preferably formed on the clamp member opposite the end 8 so that the clamp member is readily grasped by the finger and thumb to pull it to the open position. It is desirable to provide spring means tending to retain the clamp member in either the clamping or the open position. I therefore provide the spring plate 10, which is preferably formed integral with the body member 1 and underlies the same. Two flats are formed on the side 3 of the clamp member, the flat 11 engaging the spring plate in such a manner that the spring pressure tends to hold the clamp member in the clamping position while the flat 12, when engaged with the spring plate as shown particularly in Fig. 4, tends to hold the clamp member in the raised position, thus facilitating the introduction of the lace between the clamp member and knob.

The knob 12 is preferably formed by the head of a rivet or screw 13, which passes through aligned holes in the body member and clamp, and which may be upset at its inner end to secure it in position. This rivet or screw can thus be used as shown to secure the body member behind the surface of the shoe upper 14. The shoe upper, it will be noted, is provided with an opening through which the side of the clamp member connected with the adjacent journal 4 passes. Only the knob, and the clamp member will thus be exposed at the outside of the shoe.

It is, however, preferable to also secure the body member to the upper by means of the rivet 15 passing through the body member and the upper at a point remote from the knob. For some purposes it is desirable that a spring tongue should be provided to retain the free end of the lace in such a position that it is not likely to be accidentally disengaged from the clamp. For this purpose I therefore offset the end of the body member remote from the knob in

a forward direction and extend it away from the knob to form the tongue 16, the end of which is preferably rounded and somewhat inclined outwardly to facilitate a lace end being drawn underneath it as shown particularly in Fig. 1.

The method of using the device will be apparent from the drawings and from this it results that when the end of the lace 10 passing over the clamp member is pulled in a direction away from the knob 6 and substantially parallel to the body member, the portion of the lace between the knob and clamp member is securely wedged and held by friction.

Further, security is given by the pressing of the lace against the part 15 of the body member which extends beyond the knob 6.

This extension also serves to prevent the 20 edge of the upper being pinched in when the shoe is tightly laced.

What I claim as my invention is:—

1. A clamp comprising a body member having a convex knob projecting from its 25 outer face; and a clamp member formed as an open frame hinged at one side on the body member and having its opposite side adapted to co-operate with the knob at the side thereof remote from the hinge to clamp 30 a lace passing around the last mentioned side of the clamp and between it and the knob.

2. A clamp comprising a body member having a convex knob projecting from its 35 outer face; a clamp member formed as an open frame hinged at one side on the body member and having its opposite side adapted to co-operate with the knob at the side thereof remote from the hinge to clamp a lace passing round the last mentioned side of 40 the clamp and between it and the knob; and a spring plate on the body member, the hinge side of the clamp member having a flat thereon engageable by the spring plate to yieldably hold the clamp member in 45 clamping position.

3. A clamp comprising a body member having a convex knob projecting from its 50 outer face; a clamp member formed as an open frame hinged at one side on the body member and having its opposite side adapted to co-operate with the knob at the side thereof remote from the hinge to clamp a lace passing round the last mentioned side of the clamp and between it and the knob; 55 a spring plate on the body member, the hinge side of the clamp member having a flat thereon engageable by the spring plate to yieldably hold the clamp member in clamping position; and another flat thereon engageable by the spring plate to yieldably hold the clamp member in its open position.

4. A clamp comprising a body member having a convex knob projecting from its 60 outer face; a clamp member formed as an open frame hinged at one side on the body

member and having its opposite side adapted to co-operate with the knob at the side thereof remote from the hinge to clamp a lace passing round the last mentioned side of the clamp and between it and the knob; 70 and a spring plate integral with the body member, the hinge side of the clamp member having a flat thereon engageable by the spring plate to yieldably hold the clamp member in clamping position. 75

5. A clamp comprising a body member having a convex knob projecting from its outer face; a clamp member formed as an open frame hinged at one side on the body member and having its opposite side adapted 80 to co-operate with the knob at the side thereof remote from the hinge to clamp a lace passing round the last mentioned side of the clamp and between it and the knob; a spring plate integral with the body member, the hinge side of the clamp member having a flat thereon engageable by the spring plate to yieldably hold the clamp member in clamping position; and another flat thereon engageable by the spring plate to yieldably hold the clamp member in its open position. 85

6. A clamp member comprising a body member having a convex knob projecting from its outer face and having alined notches formed in its opposite sides at a point remote from the knob; and a clamp member formed as an open frame having one side offset to lie below the body member and to form at each end a journal engaging in the adjacent notch, the side of the clamp member opposite said offset side being adapted to co-operate with the knob at the side thereof remote from the offset side to clamp a lace passing round the last mentioned side of the clamp and between it and the knob. 95

7. A clamp member constructed as set forth in claim 6 in which a gap is formed through one of the sides of the clamp member between the journal and the knob engaging side through which a lace may be passed. 100

8. A clamp member constructed as set forth in claim 6 in which a gap is formed through one of the sides of the clamp member between the journal and the knob engaging side through which a lace may be passed, the free end of the knob engaging side of the clamp member being slightly upwardly turned. 115

9. A clamp member constructed as set forth in claim 6 in which a gap is formed through one of the sides of the clamp member between the journal and the knob engaging side through which a lace may be passed, the free end of the knob engaging side of the clamp member being slightly upwardly turned, and a lip being formed at the side of the clamp opposite said end engageable to lift the clamp member. 120

10. A clamp constructed as set forth in claim 1 in which the end of the body mem- 125

ber remote from the knob is offset forwardly and extended in a direction away from the knob to form a tongue.

11. A clamp member comprising a body member having a hole therein; a headed screw projecting through said hole, its head forming a convex knob projecting from the outer face of said body member; and a clamp member formed as an open frame hinged at 10 one side on the body member and having its opposite side adapted to co-operate with the knob at the side thereof remote from the hinge to clamp a lace passing round the last mentioned side of the clamp and between 15 it and the knob.

12. A clamp member comprising a body member having a hole therein; a headed screw projecting through said hole, its head forming a convex knob projecting from the outer face 20 of said body member; a clamp member formed as an open frame hinged at one side on the body member and having its opposite side adapted to co-operate with the knob at

the side thereof remote from the hinge to clamp a lace passing round the last mentioned side of the clamp and between it and the knob; and a spring plate on the body member having a hole therein for the passage of the screw, the hinge side of the clamp member having a flat thereon engageable by the spring plate to hold the clamp member in clamping position.

13. A clamp comprising a body member having a convex knob projecting from its outer face; and a clamp member formed as 35 an open frame hinged at one side on the body member and having its opposite side adapted to co-operate with the knob at the side thereof remote from the hinge to clamp a lace passing round the last mentioned side 40 of the clamp and between it and the knob; the body member extending somewhat beyond the knob.

Signed at Toronto, Canada, this 17th day of March, 1922.

ARTHUR L. COCHRANE.
